US00D544574S

(12) **United States Design Patent** (10) **Patent No.:** **US D544,574 S**
(45) **Date of Patent:** **** Jun. 12, 2007**

(54) **VALVE CARTRIDGE FOR WATERLESS URINAL**

(75) Inventor: **Stephen John Cummings**, Newport (AU)

(73) Assignee: **Caroma Industries Limited**, Brisbane, Queensland (AU)

(**) Term: **14 Years**

(21) Appl. No.: **29/229,953**

(22) Filed: **May 13, 2005**

(30) **Foreign Application Priority Data**

Nov. 15, 2004 (AU) 15284/2004

(51) **LOC (8) Cl.** 23-01

(52) **U.S. Cl.** **D23/233**

(58) **Field of Classification Search** D23/233-237, D23/244-249; 4/301, 310, 311, 679, 681; 251/343-345, 35; 137/454.2, 454.6, 489, 137/491, 493.7, 625.31, 247.25, 614.11, 614.18, 137/614.19, 625.17

See application file for complete search history.
